SYSTEM OF AND APPARATUS FOR
FLOWING WELLS

Jeddy D. Nixon, New Braunfels, Tex.

Application January 12, 1945, Serial No. 572,490

20 Claims. (Cl. 103—240)

1

This invention relates to new and useful improvements in systems of and apparatuses for flowing wells.

One object of the invention is to provide an improved system for flowing wells of the slow or low production type, which wells, due to the consolidated nature of the producing formation produce slowly or which due to the relatively small yield or low formation pressure either accumulate a relatively short column of well fluid in the well and/or build up a column of fluid very slowly; thus making ordinary producing methods expensive, wasteful and unsatisfactory. Since such wells are prone to become incrustated with paraffin, my improved method also seeks to eliminate or reduce paraffining by removing the cause.

Another object of the invention is to provide an improved system wherein small or relatively small quantities of well fluid are periodically displaced into a collection area by means of relatively small quantities of pressure fluid and the accumulation thus collected is elevated and discharged from the well with a proportionate amount of pressure fluid, whereby regular lifting stages may be maintained and pressure fluid conserved, as well as channeling of the pressure fluid through the well fluid due to the relatively short column usual in wells of the type described, is prevented.

Still another object of the invention is to provide an improved system whereby the building up of the usual short columns or long columns composed of slugs of well fluid, superimposed upon each other, is prevented and the resultant back pressure upon the formation is obviated or the waste of pressure fluid is eliminated due to the superimposing of successive slugs prior to final ejection from the well.

A further object of the invention is to provide an improved system of flowing wells wherein the well fluid is admitted from the producing formation into a receiving area in small or relatively small quantities and such quantities periodically displaced into a larger collecting area, whereby it is not necessary to wait until a column of well fluid of such length as to be economically and efficiently lifted, is built up.

A still further object of the invention is to provide an improved system of flowing wells wherein the well fluid is periodically displaced in small or relatively small quantities into a collection area by pressure fluid and after a sizeable accumulation of well fluid in the collection area is obtained, such accumulation is displaced to the

2

top of the well in a single and continuous operation, and also in which method the supply of pressure fluid to displace the well fluid is controlled from two sources, one a secondary source for intermittently causing small conserved supplies of pressure fluid to displace well fluid from the receiving area into the collecting area and the other, a primary source for causing a sufficient supply of pressure fluid to elevate and discharge the collected well fluid from the collection area, all without channeling or undue aeration, as well as without bleeding off wasteful quantities of pressure fluid.

Another object of the invention is to provide an improved system wherein the well fluid is displaced by pressure fluid in stages from the accumulating area to the collecting area and then cascaded in the collection area, whereby no hydrostatic load of well fluid is imposed upon the slug of well fluid when being displaced, other than that inherent to said slug.

A further object of the invention is to provide an improved apparatus operating in accordance with the system.

25 A further object of the invention is to provide an improved apparatus operating in accordance with the system wherein the well casing is utilized to form a collection chamber as well as one which lends itself to ready assembling and 30 installation in a well.

A still further object of the invention is to provide an improved well fluid lifting apparatus wherein a receiving chamber is located at the bottom of the well and a collection chamber is also located at the bottom of the well adjacent to the receiving chamber and connected thereto; together with a tubing or conductor extending from the collection chamber to the top of the well and a pressure fluid inlet valve connected 35 with the receiving chamber and located in the lower end portion of the well, whereby pressure fluid may be economically supplied to the chambers.

40 Another object of the invention is to provide an improved well fluid lifting apparatus wherein a collection chamber in the lower end of the well is located above and adjacent to a receiving chamber and the well fluid discharge tubing is connected to the bottom of the collection chamber, whereby well fluid accumulated in the receiving chamber may be periodically displaced therefrom, conducted to the upper end portion of the collection chamber and cascaded thereinto with displacing the hydrostatic load of previously 45 displaced accumulations.

Still another object of the invention is to provide an apparatus of the character described wherein the collection chamber is exterior of the eduction conductor and is formed between packers adjustably fastened in the casing, whereby the capacity of the chamber may be varied by vertically adjusting one of the packers and changing the lengths of the intermediate conductors, and also whereby the capacity of the collection chamber is not by the length or diameter of the eduction conductor.

A construction designed to carry out the invention will be hereinafter described together with other features of the invention.

The invention will be more readily understood from a reading of the following specification and by reference to the accompanying drawings, wherein an example of the invention is shown and wherein:

Figs. 1, 2 and 3 are views partly in section and partly in elevation and representing sequence, a well installation of an apparatus for carrying out the method.

Fig. 4 is an elevation, illustrating in general, the operating mechanism for the apparatus.

Fig. 5 is an enlarged, horizontal cross-sectional view taken on the line 5—5 of Fig. 1.

Figs. 6, 7 and 8 are enlarged, horizontal cross-sectional views taken on respective lines of Fig. 2,

Fig. 9 is a longitudinal, sectional view of the 30 automatic shift valve,

Figs. 10, 11 and 12 are views similar to Figs. 1, 2 and 3 and illustrate another form of apparatus.

Fig. 13 is an elevation of a time controlled apparatus such as may be used with the intermittents, 35 and

Fig. 14 is a view of a modified form of receiving and collection chambers, partly in elevation and partly in section.

This application is filed as a continuation-in-part of my co-pending application Serial No. 454,620, filed August 12, 1942.

In the drawings, the numeral 10 designates an upright cylindrical receiving chamber or receptacle, which is located at the bottom of the well as is shown in Fig. 3. The chamber has a reducing coupling 11 screwed into its lower end and a depending nipple 12 is screwed into this coupling. A bull-plug strainer 13 is screwed onto the lower end of the nipple. An ordinary standing valve 14, of the ball type, is mounted in the upper end of the nipple and extends upwardly in the coupling 11.

The receiving chamber 10 has a second reducing coupling 15 screwed into its upper end; while a down-flow pipe 16 has its lower end screwed into the upper end of said coupling. As is shown in Fig. 3 the usual well casing C extends slightly below the upper end of the chamber 10. A suitable packer 17 mounted in the casing, packs off between the casing and the pipe, thereby shutting off the producing formation which lies below the casing. Well fluid which may be oil and/or gas and sometimes including water, flows from the producing formation and enters the perforations of the strainer 13, from which it rises through the nipple 12 into the receiving chamber 10.

One of the features of the invention is the step in the method whereby a small or relatively small quantity of well fluid may be displaced from the receiving chamber 10, at each operation. The invention is most applicable to wells where the bottom-hole pressure is low and the well fluid does not accumulate with sufficient rapidity or rise high enough; or due to a consolidated or

"tight" formation or the comparatively small quantity of well fluid in the formation, said well does not build up a sufficient column in the well, to make ordinary lifting methods practical.

5 There are many wells which produce so slowly or in such limited quantities that in practicing the method, it becomes necessary to lift only approximately one gallon of well fluid (liquid) at each operation, while in other wells several gallons 10 may be lifted at each operation. However, the quantities will always be relatively small. The receiving chamber may be of such length as is required to carry out the method.

The principle on which the apparatus operates being to periodically displace limited accumulations of well fluid into a collecting area, pressure fluid is supplied by the pipe 16 to the upper end of the chamber. In order that this pressure fluid may act on top of the well fluid standing in the chamber, a discharge tubing 18 extends down into the said chamber. An ordinary standing valve 19 is screwed into the lower end of said tubing, a short distance above the standing valve 14. The pressure fluid forces the well fluid downwardly in the chamber 10, whereby said fluid unseats valve 19 and is elevated in the tubing. When the liquid level in the chamber goes below the valve 19, the pressure fluid escapes into the tubing.

As is shown in Fig. 2, the upper end of the down pipe 16 is screwed into the lower reduced collar 20 of a lower fitting 21. This fitting is provided with a substantially L-shaped passage 22 and the upper end of the discharge tubing 18 is screwed into the bottom of the fitting so as to discharge into the bottom of said passage. The tubing 18 is disposed at one side of the collar 20 and the flared mouth of a vertical duct 23 discharges into the collar for supplying pressure fluid to the down pipe 16. This duct 23 is arcuate in cross-section as is shown in Figs. 7 and 8. The upper end of the duct opens into a cylindrical sump 24 in the upper end of the fitting, which sump is internally screw-threaded to receive the lower end of a connecting pipe 25. A counter-bored well 26 is provided in the bottom of the sump and the lower end of an eduction tubing 27 is screwed into the upper end of said well. A port 28 leads from the bore through the fitting (Figs. 2 and 7) and discharges into the casing.

An upper fitting 29 shown in Figs. 1, 2, 5 and 6, is formed with a bore 30 extending therethrough, somewhat larger in diameter than the eduction tubing 27 which extends axially through said bore. In an actual installation the eduction tubing will not be bent as shown, since owing to the lengths of the parts, said tubing will pass through with only slight deflections. A vertical discharge tubing 31 disposed at one side of the connecting pipe 25 has its lower end screwed into the top of the lower fitting 21 in communication with the passage 22 and is provided in its upper portion with an elongate discharge slot 32. In order to anchor the upper end of said tubing, 65 a cap 33 is screwed thereonto. An anchor bolt 34 is supported in a flanged bushing 35 carried by a bracket 36 projecting laterally from the lower end of the upper fitting 29. This bolt has screw-threaded engagement in the cap 33.

The upper fitting 29 has an internally screw-threaded collar 37 at its upper end for receiving the lower end of a hanger pipe 38. A suitable packer 39 packs off between the casing and the hanger pipe. It will be observed that the lower packer 17 (Fig. 3) and the upper packer 39, pack

off a space within the casing C exterior of the elements 16, 21, 25, 29, 31 and 38 which forms a collecting chamber A, into which the slot 32 of the tubing 31, discharges. The well fluid which is elevated through the tubing 18 and passage 22 by the pressure fluid, is thus ejected into the collection chamber A and this chamber is of such size as to accumulate a sizeable quantity of well fluid, as for instance a barrel. Adjustable packers are common in the well art and the packers 17 and 39 may be vertically adjusted to vary the capacity of the collection chamber as conditions may require.

The eduction tubing 27 (Figs. 1 and 2) extends upwardly through the bore 30 of the fitting 29 into and through the hanger pipe 38. Connected in the tubing is a slip joint 40 comprising a sleeve 41 into the lower end of which the tubing is screwed. A bell 42 is formed on the upper end of the sleeve and is provided with internal packing rings 43 in which the upper length of the tubing has a sliding fit, whereby a fluid-tight joint is made. This slip joint 40 permits the upper length of tubing to be vertically adjusted.

The hanger pipe 38 is connected to the lower end of an operating valve B. As this valve may be of any suitable type, it is not considered necessary to illustrate or describe the same in detail. A valve and control apparatus such as are shown in my Patents 2,245,003, 2,202,462, and 2,245,005, may be used. The valve B has pressure fluid inlet ports 44 and suitable valve means for controlling the supply of such fluid to the hanger pipe 38; while a well tubing 45 leads from the valve for conducting well fluid from the eduction tubing.

The principle of operation involved in the invention is that of periodically lifting relatively small quantities of well fluid from the receiving chamber 10 to the collecting chamber A, by means of pressure fluid and when a sufficient quantity of well fluid has been accumulated in the collection chamber, to elevate and discharge such accumulation. Obviously, the quantity of pressure fluid required to lift a small or relatively small quantity of well fluid from the receiving chamber 10 to the collection chamber A, a distance usually less than 25 feet, is not nearly as large as the quantity of pressure fluid necessary to lift the many times larger quantity of well fluid from the collection chamber to the top of the well, a distance varying from several hundred to several thousand feet. As it also is desirable to maintain the casing C above the packer 39 full of pressure fluid and under sufficient lifting pressure, it becomes manifest that it is also desirable to conserve such pressure fluid, which is usually gas.

In order to supply the pressure fluid in accordance with the invention, I provide a primary source and a secondary source connected in common with the mechanism for actuating the valve B, and including an automatic valve for shifting the supply from one source to the other source. Here again the particular mechanisms for supplying the pressure fluid may be of any suitable type. As the primary source, an apparatus P, such as it shown in my Patent No. 2,202,462, may be used and for the secondary source an apparatus of the type shown in my Patent No. 2,171,478, may be employed.

Both of these apparatuses are time controlled and thus the secondary apparatus or intermitter S may be set to supply pressure fluid for brief periods at predetermined intervals, while the primary apparatus or intermitter P may be set to operate at the end of an overall period of proper

duration to permit the required number of secondary operations during such duration. As an illustration, the primary intermitter P may be set to operate every 7 hours; while the secondary apparatus may be set to operate at intervals of 10 minutes, skipping an operation at the time intermitter P operates. Thus, the intermitter S would operate approximately 42 times to each operation of the intermitter P. If the intermitter S displaced one gallon at each operation or stage, approximately 42 gallons (liquid) of well fluid would have been collected in the chamber A, when the intermitter P operated. A barrel of oil contains approximately 42 gallons (liquid).

I have shown the intermitter P connecting with a pressure fluid discharge pipe 50 and the intermitter S, as connected with a discharge pipe 51. The pipe 50 is connected with one side of the T-shaped casing 52 of an automatic shift valve E and the pipe 51 is connected to the opposite of said casing as is shown in Figs. 4 and 9. A pressure fluid conducting pipe 53 leads to the actuating apparatus for the valve B in the well.

A coupling 54 is screwed onto one side of the casing and the pipe 50 is screwed into this coupling. An annular beveled valve seat 55 formed in the coupling at one end of the casing. A like coupling 56 is screwed onto the opposite side of the casing and the pipe 51 is screwed thereinto. A slide valve 57 has a sliding fit in the casing 52 and is provided with a reduced shank 58 intermediate its ends. On each end of the valve a beveled annular valve disk 59 is suitably secured. The disks may be made of any suitable material, such as synthetic rubber or packing material.

In operation, one or the other of said disks is always in engagement with an adjacent valve seat 55, thus alternately closing off the pipes 50 and 51. The valve 57 is of such length that when one of the disks 59 is seated, the opposite end of the valve is in the medial portion of the casing 52, thus permitting free flow of fluid from the open seat to the pipe 53. The valve is alternately shifted from one seat to the other seat by the pressure fluid acting on the seated end of said valve.

The pipe 53 leads to an actuator which includes a cylinder 61 as is shown in Fig. 4 which contains a piston as shown in my Patent No. 2,202,462. This cylinder is suitably supported and has a piston 62 fastened to the upper end of a wire line 63 which line extends down through the well head 64 and is connected with the valve B.

In operating the apparatus, it is first installed in the well. The apparatus is hung from the pipe 45 which in turn may be suitably suspended from the well head 64. As the well casing is shut in at the surface in accordance with the usual practice, the casing space above the packer 39 forms a reservoir R which is filled with pressure fluid, such as gas, by means of the pipe 60. This gas is constantly supplied under a sufficient pressure to build up a working pressure in the reservoir, usually from 250 to 600 lbs. per square inch. Such a working pressure is substantially maintained throughout the operation.

The entire apparatus including the valve B is located at the bottom or lower end of the well. In many installations the valve B may be less than 100 feet above the base of the well in a well which may be several hundred or more than a thousand feet in depth. As set forth in my Patent No. 2,171,478, the valve B is operated by the wire line 63 which is attached to the piston 62 of the

cylinder 61 for raising and lowering the wire line and thereby operating said valve to admit and shut off the supply of pressure fluid from the reservoir R through the inlets 44.

The secondary intermitter S is of the type which is designed to operate rapidly so pressure fluid may be supplied to the cylinder 61 for a brief period of time and quickly shut off. Usually the intermitter S will open the valve B from 1 to several seconds, as very little pressure fluid, at the working pressure herein specified, will be required to lift the small quantity of well fluid from the chamber 10 to the chamber A. It will be assumed that the well has been emptied of collected well fluid and the shift valve 57 is seated at the left hand side of the casing 52 of the automatic valve E, thus shutting off flow through the pipe 51; also that well fluid has filled the receiving chamber 10 to the point where the desired and predetermined quantity has accumulated by flowing thereinto through the strainer 13 and past the standing valve 14. The timing mechanism in the intermitter S at this time operates said intermitter to release the pressure fluid which flows through the pipe 51, unseats the valve 57 and causes it to engage the opposite valve seat 55 and close off the pipe 50, whereby said pressure fluid may flow into the pipe 53.

The pressure fluid from the pipe 53 enters the actuator cylinder 61 and raises the wire line whereby the valve B (Fig. 1) is opened to admit pressure fluid through the inlets 44 from the reservoir R. This pressure fluid flows down the hanger pipe 38 to the bore 30 of fitting 29, (Figs. 1 and 2) thence by pipe 25 to the well 24 and by way of duct 23 and pipe 16 to the top of the receiving chamber 10. Usually the well fluid will rise in the chamber 10 to a point adjacent the coupling 15 (Fig. 3) and thus, the pressure fluid will be delivered on top of the accumulation of well fluid. When this occurs, the valve 14 will be closed thereby keeping the pressure off of the formation. The pressure fluid acting upon the well fluid will force it downwardly in the chamber 10, unseating the valve 19 and displacing such fluid upwardly into the discharge tubing 18, through said tubing (Fig. 2), thence through the passage 22 into the tubing 31 and thence through the slot 32 to the collection chamber A.

It is here pointed out that the slot 32 is located in the upper portion of the tubing 31 and also that the packer 17 is located some distance below said slot, thereby giving to the collection chamber a large capacity below said slot. An important feature of the invention is that the well fluid which discharges through the slot cascades or falls down into the collection chamber therebelow. Owing to the cascading of the oil in the collection chamber, no hydrostatic load from preceding displaced accumulations is imposed upon each succeeding displaced accumulation discharged into the collection chamber A.

When the liquid level of the well fluid in chamber 10 is forced below the valve 19, no additional well fluid will be displaced into the tubing 18 and when the displaced well fluid has been discharged through the slot 32, the supply of pressure fluid will be shut off. Due to the larger diameter of the collection chamber A and the considerable space therein above the slot 32, the residue of pressure fluid flowing from the slot 32, will be dissipated in the upper portion of said collection chamber. When the velocity of the pressure fluid flowing through the valve 19 recedes, said valve will close. When the valve B closes, any pressure

fluid possessing insufficient energy to unseat the valve 19, will be trapped between said valve 19 and valve B and not lost.

In order to release pressure fluid trapped in the upper portion of the collection chamber A, a relief valve 65 is provided in the fitting 29 above the bolt 34 (Fig. 2). This valve is of the ball type and is provided at the lower end of an upright passage 66 connected intermediate its ends with the bore 30 of said fitting. Whenever the pressure of the gas trapped in the collection chamber becomes sufficient, it will unseat the valve 63 and flow into the bore 30, when the valve B is closed.

As a conservation measure, the secondary intermitter is timed to shut off when the accumulation of well fluid is discharged through the slot 32 of pipe 31; thus gas is supplied only in sufficient quantity to displace the accumulation of well fluid and in this case is not lost or vented to the atmosphere.

As an illustration and in no sense, a limitation, if it is desired to collect a barrel of well fluid which may be oil, the chamber 10 may be arranged to accumulate above the valve 19, one gallon of oil. Thus in 42 successive intermittent operations, approximately a barrel of oil may be collected in the chamber A. The quantities may of course be less or greater. The collection period will vary in accordance with production of the well. Some wells may be more productive than others and thus the quantity of well fluid accumulated in chamber 10 and collected in chamber A, may vary, as well as the timing of the operations.

The primary intermitter P is of a type designed to supply a larger quantity of gas at each operation than is the secondary intermitter S. It is timed to operate when the predetermined quantity of oil has been collected in the chamber A.

In Figs. 10, 11 and 12, I have shown another form of the invention and also have further illustrated the installation. The casing C is provided with a well head 64 on which is mounted a cross T 70, from which the usual flow line 71 extends. A stuffing box 72 is mounted on the T and wire line 63 extends through this box. The T 70 is fastened to the upper end of the tubing 45 which extends down to the valve B as is shown in Figs. 10 and 11. In Fig. 11, the wire line 63 is shown attached to the upper end of a weight bar 13. This weight bar when lowered engages a plunger 74 and depresses the same to close the valve B as is clearly shown in my Patent No. 2,245,004. As before stated, it is not considered necessary to describe the valve B in detail because any valve suitable for the purpose may be used. While in the form shown in Figs. 10 and 11, the weight bar is lowered to close the valve and raised to open the valve, as in my Patent No. 2,202,462, the operation may be reversed as in my Patent Re. 21,199. Suitable kick-off valves 75 may be connected in the tubing 45 above the valve B as is common in this art; such valves are shown in my Patents 2,171,480 and 2,245,002.

The valve B is connected with a suitable gas release valve 76 such as is shown in my Patent No. 2,245,003, Fig. 13, by means of a nipple or short length of pipe 77. A suitable packer 78 is mounted on the nipple so as to pack off the casing C thereabove and form the pressure fluid reservoir R in the same manner as the packer 39 in Fig. 1. The purpose of valve 76 is to release any gas or pressure fluid from the casing below the packer to the nipple 77. The upper reduced end of an elongate receiving chamber 79 is screwed

into the lower end of the valve 76. This chamber, as shown in Figs. 11 and 12, is cylindrical in cross-section and is given sufficient length to accumulate the desired quantity of well fluid.

A discharge tubing 80 extends upwardly through the valve 76, nipple 77 to the valve B. The lower portion of this tubing is swaged or otherwise enlarged to form a cylindrical receiving chamber 79 which is disposed co-axially in a collection chamber 81 which is co-axially disposed in the casing C. The receiving chamber 79 is spaced from the casing and the collecting chamber is spaced from the receiving chamber so as to provide the necessary areas therebetween. A standing valve 83 is screwed into the lower reduced end of the chamber 81 and has a tail pipe 84 depending therefrom as is shown in Fig. 12. The tail pipe terminates above a standing valve 85 screwed into the lower reduced end of the receiving chamber 79 and supports a nipple 86 to which a bullet plug strainer 87 is attached.

The spacing between the collecting chamber 81 and the receiving chamber 79 may be very narrow because the bulk of the well fluid accumulated in the chamber 79 will be below the enlarged portion of the chamber 81. This arrangement permits a maximum diameter to be given to the collecting chamber so that its storage capacity will be adequate. Where the accumulation of well fluid in the receiving chamber is small, said fluid may submerge only a portion of the tail pipe 84.

Any suitable time controlled intermitter may be employed for supplying pressure fluid from the reservoir R to the valve B; such time controlled mechanisms are clearly shown in my patents herein enumerated. It is possible to use a single intermitter of the type shown in my Patent No. 2,245,005, and to provide reduced additional notches 88 on the wheel 111 of such patent between the notches 112 thereof, to provide for short or limited operations for displacing the well fluid from the receiving chamber 79 into the collection chamber 81 and to employ the larger notches 112 of said patent for lifting the collected load from the well, as is shown in Fig. 13.

The well fluid enters the receiving chamber 79 in the same manner as it enters the chamber 10 in Fig. 3. At suitable intervals determined by the spacing of the notches 88, relatively small amounts of pressure fluid are discharged by the valve B on top of the fluid in the chamber 79, whereby the accumulated well fluid is discharged through the tail pipe 84 past the valve 83 into the collection chamber 81. This operation is repeated until the predetermined amount of well fluid has been collected in the chamber 81, whereupon, the collection of well fluid is elevated in the tubing upon the roller 110 of the lever 105 enters the larger notch 112.

It is pointed out that the pipe 77 and tubing 80 may be of any desired length. In Fig. 14, I have shown another form of apparatus wherein the pipe 77 and tubing 80 are both lengthened and the enlarged portion of said tubing is eliminated, thus making the tubing 80 serve as the collecting chamber.

It is also pointed out that during the interval of time elapsing between the last displacement of well fluid from the receiving chamber 10 or 79 into the collecting chamber A, 81 or 80, well fluid will accumulate in the receiving chamber, therefore when pressure is supplied to lift the collected well fluid, it will first displace the accumulation from the receiving chamber. In the form shown in Figs. 1 to 9, the displaced accumulation is car-

ried into the collection chamber A and with the following pressure fluid, forces the collected well fluid which will always stand well above the port 28, into the tubing 27, so that when the pressure fluid enters said tubing the column of well fluid will be in motion and the pressure fluid will not channel therethrough. It is obvious that in the forms shown in Figs. 10 to 12 and 14, the accumulation will be displaced into the tail pipe 83 and start the collected well fluid moving upwardly, before the pressure fluid enters the collection area.

This invention seeks to conserve the pressure fluid which is usually gas, by locating the valve B at a point adjacent the receiving and collection areas, as compared with a valve at the top of the well. By this arrangement it is not necessary to fill a long pipe with gas and waste this gas in order to lift a small accumulation or a large collection of well fluid. It will be noted that the slot 32 is near the top of the discharge tubing 31 so that the collection chamber A therebelow is ample to store the desired quantity of well fluid, such as oil; also that by dumping or cascading each batch or accumulation into the chamber A, no hydrostatic load must be displaced therein. By using the casing C and the packers 17 and 39 to form the collecting chamber, not only is such chamber economically formed, but it may be lengthened or shortened at will because adjustable packers may be used.

The formation of paraffin is prevented because by accumulating and collecting the oil at the bottom of the well, the temperatures will usually be high enough to keep the paraffin in solution; and when the oil is elevated to the top of the well, it will be in sufficient volume and so rapid, as to obviate a pressure drop sufficient to paraffin the tubing. The apparatus being formed largely of tubular members lends itself to ready assembly and installation in the well under ordinary oil-field practices. The fluid which is supplied to elevate or lift the well fluid may be referred to as "pressure fluid," "lifting fluid" or "gas."

What I claim and desire to secure by Letters Patent is:

1. A system of flowing wells having casing and tubing therein which includes, means for packing off the casing and maintaining therein a reservoir of pressure fluid under working pressure, means for accumulating a relatively small quantity of well fluid at the bottom of the well in a confined area, means for periodically admitting a proportionate quantity of pressure fluid from said reservoir to the accumulating means to displace each accumulation of well fluid, whereby the well fluid is displaced in a series of stages, means for collecting the displaced well fluid in a single body in a confined area at the bottom of the well through a period of several stages of displacement until a quantity of well fluid has been collected, and means for admitting pressure fluid from the reservoir to the collecting area in sufficient quantity to displace the body of collected well fluid into the well tubing and elevate it to the top of said tubing and discharge it therefrom during a continuous operation.

2. A system of flowing wells having tubing therein which includes, means for maintaining a reservoir of pressure fluid under working pressure in the well exteriorly of the tubing, means for accumulating a body of well fluid at the bottom of the well, means for admitting pressure fluid from said reservoir at predetermined intervals to said body of accumulated well fluid to

displace it in stages, means for collecting the well fluid displaced through a series of stages into a body at the bottom of the well, and means for admitting pressure fluid from the reservoir to the body of collected well fluid for a period of time and in sufficient quantity to continuously displace the collected body of well fluid upwardly through the tubing and discharge it therefrom.

3. A system of flowing wells having tubing therein which includes, means for accumulating well fluid at the bottom of the well, means for periodically supplying pressure fluid to the accumulation of well fluid to displace it and cascade it into a collection area exteriorly of the tubing at the lower end of the well until a body of well fluid is collected, and means for supplying pressure fluid to the collected well fluid to displace it from the collection area to the tubing and elevate it in said tubing to the top of the well.

4. A system of flowing wells having tubing therein which includes, means for accumulating a small quantity of well fluid in a confined area at the bottom of the well, means for periodically supplying small quantities of lifting fluid and displacing and cascading each accumulation of well fluid into a collection area in said well until a quantity of well fluid has been collected, means for conserving the lifting fluid in the well, and means for supplying sufficient lifting fluid to the collection area to displace the collected well fluid from the well.

5. A system of flowing wells having tubing therein which includes, means for confining a supply of pressure fluid in the well, means for successively accumulating quantities of well fluid in a confined area at the bottom of a well in small individual batches, means for supplying pressure fluid to each successive batch of well fluid from a point adjacent said area to displace each batch into a collection area, means for supplying pressure fluid from a point adjacent said collection area to lift the collected batches en masse to the top of the well, and means for controlling the supplies of pressure fluid from the top of the well.

6. A system of flowing wells having tubing therein which includes, means for successively accumulating quantities of well fluid in a confined area at the bottom of a well in small individual batches, means for supplying pressure fluid to each successive batch of well fluid from a point adjacent said area to elevate it in the well, means for cascading each elevated batch into a confined collection area, means for supplying fluid from a point adjacent said collection area to lift the collected batches en masse to the top of the well, and means for controlling the supplies of pressure fluid from the top of the well.

7. A system of flowing wells having tubing therein which includes, means for successively accumulating quantities of well fluid in a confined area at the bottom of a well in small individual batches, means for supplying pressure fluid to each successive batch of well fluid from a point adjacent said area to elevate it in the well, means for cascading each elevated batch into a confined collection area, means for supplying fluid from a point adjacent said collection area to lift the collected batches en masse to the top of the well, and means for automatically controlling the supplies of pressure fluid from the top of the well.

8. A system of flowing wells having tubing therein which includes, means for accumulating a small quantity of well fluid in a confined area at the bottom of the well, means for periodically

supplying small quantities of lifting fluid and displacing and cascading each accumulation of well fluid into a collection area in said well until a quantity of well fluid has been collected, means for collecting and trapping the pressure fluid expended in lifting each accumulation, and means for supplying sufficient lifting fluid to the collection area to displace the collected well fluid from the well.

9. A system of flowing wells wherein a body of lifting fluid is stored in the casing under oil-lifting pressure and an eduction tubing is disposed in the casing which includes, means for accumulating a body of oil in the well, means for supplying the lifting fluid at predetermined intervals to said body of accumulated oil to displace it in stages, means for collecting the oil displaced through a series of stages into a body of predetermined volume at the bottom of the well, and means for supplying the lifting fluid to the collected body of oil for a period of time and in quantity sufficient to continuously lift the collected body of oil through the tubing of the well and discharge it therefrom.

10. A system of flowing wells wherein a body of lifting fluid is stored in the casing under oil-lifting pressure and an eduction tubing is disposed in the casing which includes, means for accumulating oil from the formation in a confined area at intervals of time, means for periodically supplying the lifting fluid to the accumulated oil to displace it into a collecting area, means for collecting the displaced oil in such area during such periods until a body of oil is collected equal to at least one barrel at the bottom of the well, and means for supplying the lifting fluid to the collected body of oil to continuously lift it through the tubing of the well and discharge it therefrom.

11. A system of flowing wells wherein a body of lifting fluid is stored in the casing under oil-lifting pressure and an eduction tubing is disposed in the casing which includes, a receiving chamber having a standing valve located below the liquid level in the well for admitting and trapping oil therein, an oil collecting chamber connected with

the tubing and also connected with the receiving chamber for receiving fluid therefrom, the collecting chamber having a capacity for storing the quantity of oil to be ejected from the well during a single lifting operation, means for retaining oil in the collecting chamber adapted to open in response to fluid pressure, means for supplying fluid pressure from the well casing to the receiving chamber to displace oil therefrom into the collecting chamber.

surface-controlled means for actuating the fluid pressure supply means, and time-controlled means for operating the surface controlled apparatus having means for causing the operation of the surface-controlled means and the fluid pressure supply means to periodically supply pressure fluid to the receiving chamber to displace oil therefrom into the collecting chamber without displacing said oil from the collecting chamber and to periodically supply pressure fluid to the collecting chamber in sufficient quantity

to discharge the collected oil from the collecting chamber into the tubing and eject said oil from the tubing at the surface of the well.

12. A system of flowing wells having casing and tubing therein which includes, means in the casing providing a reservoir of pressure fluid, a receiving chamber disposed in the well below the liquid level therein, means in the well adjacent the receiving chamber for supplying pressure fluid from said reservoir to the receiving chamber to

displace oil therefrom, a collecting chamber at the bottom of the well connected with the tubing and communicating with the receiving chamber for receiving well and pressure fluid therefrom, and surface operating apparatus having means including a time-controlled device for periodically operating the lifting fluid supply means to supply lifting fluid to the receiving chamber to displace oil therefrom into the collecting chamber and to subsequently supply lifting fluid to the collecting chamber to displace oil therefrom into the tubing and eject such oil from the tubing.

13. A system as set forth in claim 12 wherein the time-controlled device includes a movable member having elements spaced to cause operation of the fluid pressure supply means at predetermined intervals of time and each for a predetermined duration of time and at least one element to cause said operation subsequent to the other elements and for longer duration of time.

14. A well fluid lifting apparatus for wells having tubing therein including, a vertically elongated receiving chamber adapted to be located in a well below the liquid level therein for receiving oil from the well, a vertically elongated collecting chamber connected with the tubing having an inlet at its lower end extending into the receiving chamber, a valve for admitting fluid to the collecting chamber and retaining liquid therein, a pressure fluid inlet valve mounted in the well tubing and connected with the receiving chamber for supplying lifting fluid to the receiving chamber to displace oil therefrom to the collecting chamber, whereby said lifting fluid is supplied also to the collecting chamber when a predetermined quantity of oil has been displaced from the receiving chamber, surface-controlled means for opening the pressure-fluid admitting valve, and apparatus on the surface for periodically operating said surface-controlled means having means for causing a series of operations of predetermined periods of time and a subsequent operation for a longer period of time, whereby oil is accumulated in the collecting chamber in a series of displacements from the receiving chamber and the collected oil raised from the collecting chamber by the lifting fluid.

15. A system of flowing wells having tubing therein which includes, a receiving chamber disposed in the well having an inlet below the liquid level therein, means mounted in the well tubing for supplying lifting fluid to the receiving chamber to displace oil therefrom, a collecting chamber wholly at the bottom of the well adapted to be connected with the well tubing and connected with the receiving chamber to receive fluid displaced therefrom and having means for retaining oil therein, means for operating the lifting fluid supply means to displace oil from the receiving chamber into the collecting chamber in a series of stages until a load of oil has been collected in the collecting chamber, and means for supplying lifting fluid to the collecting chamber to raise in the well tubing the load of collected oil and to discharge it from the well.

16. A well fluid lifting apparatus including, an eduction tubing, a pressure inlet valve connected to said tubing, a receiving chamber adapted to be mounted at the bottom of a well, a conductor connecting the receiving chamber with the valve for supplying pressure fluid to the receiving chamber to displace fluid therefrom, a collec-

tion chamber exterior of the eduction tubing and conductor, a discharge conductor leading from the receiving chamber to the collection chamber for conducting fluid, and a fluid discharge tubing between the collection chamber and the valve.

17. A well fluid lifting apparatus including, an eduction tubing, a collection chamber connected with the eduction tubing, a receiving chamber connected with the collection chamber and adapted to be mounted at the bottom of a well, said receiving chamber having a well fluid inlet, means for supplying pressure fluid to the receiving chamber to displace well fluid therefrom into the collection chamber, a valve adapted to be located in a well connected to the eduction tubing and to the means for supplying pressure fluid, surface means for operating said valve, secondary means for actuating the surface means for brief successive periods to operate the valve to periodically supply small quantities of pressure fluid to the receiving chamber, and primary means for actuating the surface means to operate the valve to supply pressure fluid to the receiving and collection chambers to displace collected well fluid through the eduction tubing to the top of a well.

18. A system of flowing wells having tubing therein including, means for packing off the well and maintaining therein a reservoir of pressure fluid, a well fluid accumulating chamber having an inlet below the liquid level in the well, a collecting chamber in the well connected with the accumulating chamber and the well tubing, means for admitting pressure fluid from the reservoir in the well to displace accumulations of well fluid from the accumulating chamber to the collection chamber prior to discharging such accumulations into the well tubing, and means for admitting pressure fluid from the reservoir to the collection chamber for discharging the accumulated well fluid therefrom into the well tubing and to the top of the well.

19. A system of flowing wells having tubing therein, means for packing off the well and maintaining therein a reservoir of pressure fluid, a well fluid accumulating chamber having an inlet below the liquid level in the well, means for packing off the well casing to provide a collecting chamber in the well connected with the accumulating chamber and the well tubing, means for admitting pressure fluid from the reservoir in the well to displace accumulations of well fluid from the accumulating chamber to the collection chamber prior to discharging such accumulations into the well tubing, and means for admitting pressure fluid from the reservoir to the collection chamber for discharging the accumulated well fluid therefrom into the well tubing and to the top of the well.

20. A well fluid lifting apparatus including, an elongate tubular accumulating chamber, a pressure fluid conductor connected with said accumulating chamber, a well fluid conductor extending upwardly from the accumulating chamber and having a discharge opening, packers engaging with the pressure fluid conductor above and below the discharge of the well fluid conductor, well fluid eduction tubing having an inlet between said packers, and means for supplying pressure fluid to the pressure fluid conductor.
